UNITED STATES PATENT OFFICE.

ROBERT B. WOODWORTH, OF PITTSBURG, PENNSYLVANIA.

METALLIC TUNNEL-LINING.

984,387.

Specification of Letters Patent. Patented Feb. 14, 1911.

Application filed December 17, 1909. Serial No. 533,651.

To all whom it may concern:

Be it known that I, ROBERT B. WOODWORTH, of Pittsburg, Allegheny county, and State of Pennsylvania, have invented a new and useful Improvement in Metallic Tunnel-Linings, of which the following is a full, clear, and exact description, reference being had to the accompanying drawings, forming part of this specification, in which—

10 Figure 1 is a partial plan and Fig. 2 a transverse section on the line II—II of Fig. 1 showing a tunnel lining made in accordance with my invention. Fig. 3 is a detail sectional end view on a larger scale showing 15 the construction of the longitudinal joints in the lining and the manner in which the lining is caulked in making fluid pressure tight joints. Fig. 4 is a detail longitudinal sectional view taken on the line IV—IV of 20 Fig. 3 and showing the construction of the transverse joints in the tunnel lining shown in Figs. 1, 2 and 3, and the manner in which the joints in this construction are caulked. Fig. 5 is a detail perspective view showing 25 the manner in which the sections forming the tunnel lining of Figs. 1, 2 and 3 are assembled together in place.

My invention relates to the construction of metallic linings for tunnels, conduits and 30 similar openings and the object of the invention is to provide a metallic tunnel lining of novel construction in which standard rolled metal shapes are employed in forming the lining.

35 A further object of the invention is to provide a tunnel lining having novel means for inserting the shutter or closing plate in place in segments of the lining as completed and to provide improved means for caulk- 40 ing the lining in rendering it water or air tight.

In the drawings, a segmental lining is shown which is formed of built-up segments constructed and arranged in accordance with my invention. The lining is built up in 45 place in the tunnel as the excavation proceeds and after all of the segments forming a section are assembled together the space between the earth walls of the tunnel and the outer surface of the lining is filled with 50 grout or cement.

Each section of the tunnel is preferably made up of a number of symmetrical segments 2, which are identical in construction, and of sections 3 and 4 each having one end 55 constructed the same as that of its adjoining section 2 and each have one end con-

structed so as to fit the shutter plate 5 by which the ring of segments is completed to form a section of the tunnel. The segments 2 are formed of standard rolled metal 60 channel beams having a web portion 6 and flange portions 7. At the end of each section an angle iron 8 is secured by rivets 9 and at suitable distances in the length of each section stiffening angles 10 are securely 65 riveted to the web 6 of the channels.

The abutting faces of the angles 8 on the sections 2 radiate from a common center while the sections 3 and 4 each in one end have one angle which radiates from the 70 center of curvature and on the opposite end of each of these sections an angle which is in a non-radial position and which is arranged to be parallel with the faces of the 75 end angles on the shutter plate 5.

The faces of the integral flanges 7 on the channels forming the sections 2, 3, 4 and 5 are parallel and are provided with suitable openings through which rivets or bolts 12 are inserted in securing the sections to- 80 together.

Each ring of the tunnel formed of the sections 2, 3, 4 and 5 is staggered relatively to the adjoining section so that the longitudinal joints are broken and the shutter plate 85 in any one section is not opposite the shutter plate on the adjoining sections, this construction being best shown in Fig. 1.

As shown in Figs. 1 to 5, the segments forming each section of the tunnel lining are 90 formed of rolled metal channel beams as before and are provided on their ends with securing angles. The channels are provided with flanges of varying lengths, one flange 95 being slightly wider than that on the opposite edge of the web of the channel. The end connecting angles are also made with the leg on one angle longer than that of the abutting leg of the angle on the adjoining segment of the lining, in this way provision 100 being made for caulk- 105 ing the lining so as to provide a water tight joint between the sections.

The bolts are provided with taper washers on account of the tapering inner surfaces on the flanges of the channel beams.

In the erection of a tunnel made up of segments constructed as shown and described, the segments 2, in each section are placed in position in the tunnel and are 110 secured together by means of bolts or rivets as desired. The segments 3 and 4 are put

into place, preferably at the top of the lining in the location shown in the drawings. After the segments 2, 3 and 4 have been assembled in place, the shutter plate 5 is 5 inserted, the parallel or reversely tapered sides of this shutter plate permitting its being placed in position after the other of its segments are in place. The successive sections are put into place in a similar manner and the circumferential joints are made 10 by means of rivets or bolts.

After the sections are in place grout is pumped or caused to flow into the space between the earth wall of the tunnel and 15 the outer surface of the lining. The joints are then calked by a calking tool in the ordinary manner, the short leg on one of each of the two angles forming the connection between the sections lending itself to 20 further the calking operation.

The advantages of my invention will be apparent to those skilled in the art. A tunnel lining constructed as shown and described is simple and can be easily and 25 cheaply made. The sections are made of such size as to be easily transported and handled in being put into place. By using standard rolled metal shapes, the amount of shop work necessary is reduced. The parallel 30 edges of the rolled metal shapes are sufficiently accurate to not require machining in order to make tight joints, and in this way the cost of forming the segments is greatly reduced.

35 Modifications in the construction and arrangement of the parts may be made without departing from my invention.

I claim:

1. A sectional metal tunnel lining, the sections comprising a plurality of segments 40 and a shutter plate formed of rolled metal channel beams, said shutter plate being adapted to be inserted in place after its

adjoining segments have been erected the adjoining flanges of adjacent segments varying in width; substantially as described. 45

2. A tunnel lining comprising a plurality of annular sections, each section having a plurality of segments formed of rolled metal channel beams, means on each segment for 50 detachably securing the segments together, the adjacent flanges of adjoining segments varying in width; substantially as described.

3. In a metallic tunnel lining, a lining segment formed from a rolled metal channel 55 beam, and having means on its ends by which the segments are secured together when assembled in place, the flanges on one side and end of each segment being of less width than those on its opposite side and 60 end; substantially as described.

4. In a metallic tunnel lining, a lining segment formed from a rolled metal channel beam, and having means on its ends by which the segments are secured together, the 65 flanged edges on one side and end of each segment being of less width than the flanges on the adjoining end and side of the adjacent segment; substantially as described.

5. A metallic tunnel lining comprising a 70 plurality of annular sections each section having flanged marginal edges, the adjacent flanges of adjoining segments varying in width to provide for calking; substantially as described. 75

6. In a metallic tunnel lining, a segment having flanges on its marginal edges, the flanges on one side and end thereof being of less width than those on the opposite side and end; substantially as described. 80

In testimony whereof, I have hereunto set my hand.

ROBERT B. WOODWORTH.
